UNITED STATES PATENT OFFICE.

SARAH WRIGHT, OF BATTLE CREEK, MICHIGAN.

WASHING-MACHINE.

SPECIFICATION forming part of Letters Patent No. 276,126, dated April 17, 1883.

Application filed July 31, 1882. (Model.)

To all whom it may concern:

Be it known that I, SARAH WRIGHT, of Battle Creek, in the county of Calhoun and State of Michigan, have invented certain new and useful Improvements in Washing Apparatus; and I do hereby declare that the following is a full, clear, and exact description thereof, reference being had to the accompanying drawings, and to the letters of reference marked thereon, making part of this specification.

This invention has for its object to provide an improved machine whereby the rubbing necessary to remove the dirt from the articles being washed may be accomplished and the cleansing thoroughly effected, as more fully hereinafter set forth. These objects I accomplish by the means illustrated in the accompanying drawings, in which—

Figure 1 represents a perspective view of my improved machine, showing the same applied to a tub; and Fig. 2, a longitudinal sectional view of my machine.

The letter A indicates a wash-board having a raised rubbing-surface, corrugated as shown.

B indicates a frame constructed of wire or other suitable material. The said frame is provided with a series of longitudinal wires, C, and two short wires, C', which are hooked at their lower ends, so as to engage the lower edge of the raised portion of the board, and the frame is also provided with a hook, D, at its top, by means of which it can be clamped upon the face of the board, so that the longitudinal wires C will hold the clothes during the rubbing. The upper part of the sides of the frame form guides or ways, to which is attached a brush, E, by means of staples F, which

permits the brush to be reciprocated. To the brush is secured a wire frame, G, by means of which the brush may be operated, and to said frame is loosely attached, by means of a wire, H, hooked at the ends, a rectangular frame, I, which is designed to contain a cake of soap, as shown.

The board is placed in the tub in the usual manner, the clothes being previously placed therein in the suds. The clothes are then arranged and clamped upon the board, and the cleansing effected by reciprocating the rubbing mechanism back and forth.

Having thus described my invention, what I claim, and desire to secure by Letters Patent, is—

1. In a washing-machine, the combination, with the wash-board having a raised corrugated rubbing-surface, of the detachable frame, adapted to be secured to the board over the clothes, said frame forming guides or ways on which the brush reciprocates, substantially as specified.

2. In a washing-machine, the combination, with the clamping-frame forming guides or ways, of the reciprocating brush and the soap-frame loosely attached thereto, said brush and soap-frame being adapted to reciprocate on and within the frame-guides, substantially as shown and described.

In testimony whereof I affix my signature, in presence of two witnesses, this 23d day of May, 1882.

SARAH WRIGHT.
